UNITED STATES PATENT OFFICE.

HENRY A. BLOEDORN, OF REEDSVILLE, WISCONSIN.

PUMP.

1,329,950.

Specification of Letters Patent.

Patented Feb. 3, 1920.

Application filed March 22, 1919. Serial No. 284,271.

To all whom it may concern:

Be it known that I, HENRY A. BLOEDORN, a citizen of the United States, residing at Reedsville, in the county of Manitowoc and 5 State of Wisconsin, have invented certain new and useful Improvements in Pumps, of which the following is a specification.

This invention relates to pumps and has for its object to provide at a point inter- 10 mediate the main pump cylinder and the pump spout a supplementary cylinder and piston which acts upon the return stroke of the pump rod to force water up into the spout.

15 With the above and other objects in view as will appear as the description proceeds, the invention comprises the novel features of construction, combination of elements and arrangement of parts which will be 20 more fully described in the following specification and set forth with particularity in the claims appended hereto.

In the drawings:

Figure 1 represents a side elevation of a 25 pump illustrating the invention applied to use,

Fig. 2 represents an enlarged longitudinal sectional view through the supplementary pump cylinder, and 30 Fig. 3 represents a transverse sectional view through the supplementary cylinder.

Referring to the drawings in detail, wherein similar reference numerals designate corresponding parts throughout the 35 several views, the numeral 5 indicates the supporting base or flange carried by the hollow pump stand 6 provided with a hollow extension 7 for connection with a pipe whereby the water pumped may be con- 40 nveyed to any desired point. At a point opposite the extension 7 the stand is provided with the usual outlook spout 8 having a valve 9 therein for controlling the passage of water therethrough and the upper ter- 45 minal of the stand is finally restricted and provided with a cap 10 through which the pump rod 11 extends. The upper terminal of the rod is connected with the pump handle or lever 12 pivotally supported in a 50 bracket 13.

Beneath the platform on which the stand is supported is arranged the barrel 15 which is secured at its upper terminal in the stand and is connected at its lower terminal with 55 the cylinder 16 in which is arranged any preferred type of pump operable during

reciprocation of the rod 11 to elevate a column of water in the barrel.

The barrel 15 is divided into two sections at a point below the platform and the upper section is connected with a cap 17 while the lower section is connected at its upper end with a cap 18, the caps 17 and 18 forming the terminals of a supplementary pump housing 19.

60 The cylinder is provided with internal longitudinal ribs 20 arranged in pairs and supporting a supplementary pump cylinder 21 through which the rod 11 extends. The lower end of the supplementary cylinder is 70 open and the upper end thereof is restricted in diameter and fitted or otherwise connected with a tubular housing 22 which extends upwardly through the barrel 15, stand 6 and is attached to and supported by the 75 cap 10.

Within the cylinder the rod 11 is provided with a stop collar 23 constituting an abutment for the piston 24 carrying a flanged packing ring 25 secured in position 80 upon the rod by a nut 26 threaded or otherwise secured thereon. The flange of the packing ring 25 is arranged so as to prevent the passage of water upwardly past the piston into the tubular housing 22 and the 85 head enters the cylinder through the lower open end thereof. Drain pipes 27 are connected with the restricted upper portion of the supplementary pump cylinder and extend through the wall of the housing 19 and 90 are designed to permit the water which might leak past the ring 25 and in through the tubular housing 22 to flow back into the well.

95 In operation, during the up stroke of the pump rod 11 water is lifted into the cylinder 16 of the main pump and during the subsequent down stroke of the piston is forced upwardly through the barrel 15. When the column of water in the barrel 100 reaches a height above the supplementary cylinder 21 the piston 25 acts, during the down stroke of the rod 11, to force the column of water upwardly through the barrel 105 and out through the spout 8.

What I claim is:

1. In combination, a main pump includ- 110 ing a cylinder and rod, a sectional barrel connected with the cylinder, a housing connecting the adjacent terminals of the barrel sections, a supplementary cylinder arranged in concentrically spaced relation to the hous-

ing, a tubular housing extending upwardly from the supplementary cylinder through the barrel and receiving the rod, a supplementary piston carried by the rod reciprocably mounted in the supplementary cylinder and spaced supporting ribs extending from end to end of the supplementary cylinder and connected with the housing for rigidly maintaining the supplementary cylinder in concentrically spaced relation thereto.

2. In combination, a main pump including a cylinder and rod, a sectional barrel connected with the cylinder, a housing connecting the adjacent terminals of the barrel sections, a supplementary cylinder arranged in concentrically spaced relation to the housing and having a restricted upper terminal, a tubular housing connected with the upper restricted portion of the supplementary cyl-

inder receiving the rod, a piston carried by the rod reciprocably mounted in the supplementary cylinder, a packing ring arranged to prevent the passage of liquid between the piston and supplementary cylinder wall, spaced supporting ribs extending from end to end of the supplementary cylinder and connected with the housing for rigidly maintaining the supplementary cylinder in concentric relation thereto throughout its entire length, and drain pipes connected with the upper restricted portion of the supplementary cylinder above the piston therein and extending through the housing to assist in maintaining the supplementary cylinder in position.

In testimony whereof, I affix my signature hereto.

HENRY A. BLOEDORN.
